UNITED STATES PATENT OFFICE.

FRANK C. MOCK, OF CHICAGO, ILLINOIS, ASSIGNOR TO STROMBERG MOTOR DEVICES COMPANY, OF CHICAGO, ILLINOIS, A CORPORATION OF ILLINOIS.

FUEL-FOGGING DEVICE FOR INTERNAL-COMBUSTION ENGINES.

Application filed October 31, 1919. Serial No. 334,895.

To all whom it may concern:

Be it known that I, FRANK C. MOCK, a citizen of the United States, residing at Chicago, in the county of Cook and State of Illinois, have invented a certain new and useful Improvement in Fuel-Fogging Devices for Internal-Combustion Engines, of which the following is a full, clear, concise, and exact description, reference being had 10 to the accompanying drawings, forming a part of this specification.

This invention relates to fuel fogging device for internal combustion engines.

Devices heretofore constructed for this 15 purpose ordinarily depend for their action upon the heating of the entire fuel mixture before it enters the engine cylinders. That is, the intake manifold or a portion thereof is heated by the engine exhaust so as to evaporate the unvaporized particles of the fuel as they are carried therethru by the mixture. Such a scheme, however, has its objectional features. In the first place the volumetric expansion of the air of the mixture, due to 20 the increased temperature, causes an actual reduction, by weight, of the mixture drawn into the cylinders with a consequent reduction in power. In the second place the unvaporized particles are carried thru the manifold with such speed that all are not effected by the increased temperature with the result that complete evaporation is not 25 effected.

Attempts to complete vaporization in applying excessive heat tends to overheat the cylinder walls and cause sticking of the cylinder due to lack of lubrication at the high 30 temperature.

The general aim of the present invention 35 is to provide an improved device for this purpose which will be free from the above objections.

The primary object of my invention is 40 to construct means for producing a dry mixture composed of fuel vapor and air in proper proportion. This I accomplish by vaporizing the unvaporized particles of fuel carried in the main body of air, these particles being separated, vaporized, and then reduced to a fine degree of 45 condensation, or in other words, reduced to a fine fog which permits of equal distribution and complete combustion, this fog existing at a much lower temperature than a dry

charge. This increases the weight of charge 55 and reduces the tendency to detonate or knock.

In attempting to secure complete fogging, the time factor is of great importance, because with different quantities of fuel fed at 60 different engine speeds, and the different degrees of heat available at the different temperatures of motor operation, the time required for converting the fuel into fog varies greatly; therefore, necessitating complete separation of the unfogged or unvaporized fuel drops from the remainder of 65 the mixture as the same passes to the engine. I am aware that attempts have been made to heat the fuel and not the air, but the devices 70 heretofore developed for this purpose are so complicated that practically few have gone beyond the status of laboratory experiment.

Another object of my invention is to construct a device of the class referred to which 75 is simple in construction, durable, economic in use and readily associated with the standard carburetor and internal combustion engine of to-day.

Other more specific objects and advantages will hereinafter appear.

One embodiment of the invention is illustrated in the accompanying drawings.

The views of the drawings are as follows:

Figure 1 is a fragmentary side elevation of 80 a motor of standard type illustrating an application of the invention thereto;

Figure 2 is a vertical transverse section on a larger scale of the fuel vaporizer applied to the motor of Figure 1. This section is 85 taken substantially on the line 2—2 of Figure 3;

Figure 3 is a vertical longitudinal section taken substantially on the line 3—3 of Figure 2, and

Figure 4 is a vertical sectional view of a modified form of my invention.

The motor 10 illustrated in Figure 1 is of a well known or standard type and is provided with the usual exhaust manifold 11 and intake manifold 12. A fuel fogging device 13, made in accordance with the present invention, is mounted upon and communicates with the receiving end 14 of the intake manifold. A carburetor 15 of any approved 100 type is carried by and communicates with the fogging device 13 through the usual pipe 16, constituting part of the equipment of the 105

carburetor. The connections are such that the fuel mixture passes from the carburetor through the fogging device and finally enters the engine cylinders through the intake manifold.

The necessary heat for vaporizing the unvaporized fuel particles is preferably obtained from the exhaust manifold 11 by any appropriate means such as a branch pipe 17 leading from the manifold to the fogging device. After passing through the fogging device these exhaust gases may be led away through a pipe 18.

The invention shown in Figures 2 and 3 includes a main body portion 19 preferably in the form of a hollow casting generally annular in configuration. The substantially cylindrical chamber 20 formed therein constitutes the separating chamber 20 while the annular channel 21 forms the passage through which the exhaust gases from the engine are caused to pass in order to heat the cylindrical wall only of the separating chamber. A series of fins 22 are preferably provided upon the outer side of the separating chamber wall and projecting within the annular channel in order to increase the heating effect of the exhaust gases.

As previously pointed out the exhaust gases are delivered to the annular channel 20 through the pipe 17 from the exhaust manifold. For this purpose an intake 23 is preferably formed integral with the main body portion 19 for connection with the end of pipe 17. The exhaust gases enter from the pipe through the passageway 24 in the intake 23, circulate through the channel 21, to heat the fins 22 and hence the cylindrical wall of the separating chamber, and then pass out through an opening 25 and a passageway 26 to the exhaust pipe 18.

An intake 27 for the fuel mixture is preferably formed as an integral part of the main body portion 19 and includes a passageway 28 to the interior of the cylindrical separating chamber 20. The passageway 28 is preferably curved tangentially relative the cylindrical chamber 20, so that the excessively large particles of fuel contained in the mixture will strike the outer wall of the passageway so as to more readily vaporize such particles. The inner end of the passageway at its joining with the chamber 20 is preferably flared so as to distribute the mixture in the chamber. As shown in Figure 2 this intake is preferably provided with a flange 29 forming a seat for engagement with a corresponding seat with which a standard carburetor is usually provided. The passageway 28 is tangentially disposed with respect to the cylindrical separating chamber so that the fuel mixture from the carburetor is caused to enter the separating chamber with a

swirling action, thus by centrifugal force throwing the heavy unfogged fuel particles against the cylindrical wall of the chamber.

Means is provided for leading away the gaseous fuel mixture from the separating chamber and for permitting the unfogged particles to remain on the hot walls of the chamber. In the present instance this is accomplished by means of an axially disposed tube 30 preferably extending into the interior of the separating chamber through an opening defined by an interior annular flange 31. Flange 31 insures a proper spacing of the tube from the cylindrical wall of the chamber so that the unfogged particles are not drawn into the tube with the rest of the gaseous mixture. The gaseous mixture free from the unfogged particles is thus drawn through the tube into the intake manifold by way of the passageway 32 and finally delivered to the engine cylinder.

As a further means for retaining the unfogged particles upon the cylindrical wall of the separating chamber, the wall may be transversely grooved as shown at 33. After the particles have been thrown into these grooves by the centrifugal action above described, they are free from the currents of gas passing out of the chamber.

These particles are thus retained upon the wall until they have been completely reduced into a vapor due to the high temperature of the wall. This vapor coming in contact with the relatively cooler air currents condenses into a fog film which bit by bit is picked off by the air currents and gas and unites therewith to form a highly volatile mixture. This fog film is continually forming, and being interposed between the heated wall and the gaseous mixture passing through the chamber, insulates the mixture and prevents overheating. Thus, I am enabled to reduce the unfogged fuel particles to a fine fog without undue heating of the explosive mixture.

The outlet 34 for the exhaust gases and the outlet 35 for the fuel mixture preferably form parts of a single casting 36 secured by any convenient means such as bolts 37 to the main body portion 19. The adjacent walls of the fuel mixture outlet 35 and the exhaust gas outlet 34 are separated as at 35' to permit air to circulate between the same, the object being to confine the heated area of the device to the cylindrical walls. (See Figure 3.) The tube 30 is preferably rigidly retained in position by a threaded engagement with a flange 38 formed upon the casting 36. A limiting annular shoulder 39 is preferably formed upon the tube for engagement with the annular flange 31.

One end of the chamber 20 is preferably closed by a removable cap 40 which in this

instance is screwed on to a projecting flange 41 formed on the main body portion 19 for this purpose. Such a construction permits ready access to the interior of the 5 separating chamber for purposes of cleaning and inspection and for inserting or removing the tube 30.

A brief summary of the operation of the device will now be given. The hot gases 10 from the exhaust manifold 11 are led thru the branch pipe 17 and passageway 24 to and thru the annular channel 21 and then out thru the opening 25 and passageway 26 to the exhaust pipe 18. All or a portion 15 of the exhaust gases may be directed thru the branch pipe 17 by means of a throttle valve 42 of any appropriate construction arranged in the main exhaust pipe 11'. Upon striking the fins 22 the heat of these 20 gases is transmitted to the cylindrical wall of the separating chamber 20. It may be desirable in some cases to connect the valve 42 with the engine throttle so that the 25 degree of heat imparted thru the cylinder wall may be varied inversely as the speed of the engine varies. Thus, at low speeds when the velocity of air is relatively slow, a greater degree of heat is applied to the cylindrical wall for producing the fog, and 30 when the engine is running at high speed and the mechanical atomization is more perfect, the degree of heat is reduced. This action in itself is somewhat automatic in the device, but may be assisted by such 35 a control means for heat.

The fuel mixture from the carburetor is at the same time caused to enter the separating chamber with a swirling action due to the tangential relation of the inlet passage- 40 way 28 with respect to the chamber. The suspended unvaporized fuel particles are thus thrown by centrifugal force against the wall of the chamber while the remaining gaseous portion of the mixture passes 45 out through the tube 30 and passageway 32 to and through the intake manifold 12 to the engine cylinders. As the unvaporized fuel particles are thus thrown against the cylindrical wall of the chamber they are 50 reduced to vapor, and this vapor coming in contact with the relatively cooler column of air and gas partly condenses the vapor to a fine fog. Due to the formation of the film of fog on the wall of the chamber and 55 the speed of the gaseous mixture therethrough, the latter is insulated from the heated surface and therefore the temperature of the mixture is not materially increased. These fuel particles, however, are 60 continually being vaporized and condensed to fog, in the latter state uniting with the fuel mixture and passing into the intake manifold.

Thus it will be seen that this device provides a trap for the unvaporized fuel par-

ticles which actually prevents their entry into the engine cylinders until complete fogging of same occurs. Since the rate of fogging under normal running conditions is substantially constant that objectionable 70 effect commonly known as "loading" can never occur.

Furthermore the device has proven extremely flexible on acceleration from low speeds. This is due to the fact that when 75 running at idle or low speeds the deposit of unvaporized fuel on the chamber walls is very small with the result that the temperature of the walls increases. Thus when a greater volume of fuel passes through the 80 chamber, as upon acceleration, this temporary increased temperature momentarily causes a more rapid vaporization of the unvaporized fuel and consequent production of fog, resulting in richer mixture, this 85 function being enhanced by the control of heat to the cylindrical wall.

As pointed out hereinbefore, I endeavor to confine the actual heating area of the device to the cylindrical wall only, and 90 while the mixture inlet 27 does extend through the annular heating chamber, the area exposed is short and will have a very limited effect on the fuel mixture passing 95 therethrough.

In Figure 4 I have illustrated a modified form of my invention. In some cases it may be desirable to employ a vertical separator, and with this in mind I have provided the device shown in Figure 4, comprising preferably a body 45 having a peripheral wall 46, provided with inlet and outlet exhaust connection flanges 47 and 48, respectively. A cylindrical wall 49 extends vertically in the body 45 to form a cylindrical chamber 50, to be known as the separating chamber. The outer wall of the body 45 and the cylindrical wall 49 form an annular chamber 51 around which the exhaust gases from the engine are to pass. A plurality of annular exterior flanges 52 are provided on the wall 49 and a plurality of similar flanges 53 are interiorly arranged on said wall. A fuel inlet 54 is provided, the same curving upwardly and toward the separating chamber 50, and communicating therewith as at 55, the mouth of the inlet 54 being flared so as to distribute the fuel along the axis of said separating chamber. An outlet 56 is provided for the fuel, the outlet 56 being provided with depending flange 57, functioning similarly to the flange 30 described hereinbefore. The portion of the body forming the lower end wall of the separating chamber is formed with a conical extension 58, projecting upwardly into said chamber to form an annular channel to receive an excess of fuel when the engine is running at low speed.

The device illustrated in Figure 4 is, in 130

operation, practically identical to that of the first form of my invention described. The gas enters at the inlet 54, is tangentially directed into the separating chamber 5 and passes out thoroughly fogged through the outlet 56.

By actual tests of my invention I have found the same to make possible the use of lower grades of gasoline and kerosene than the ordinary internal combustion engine and in connection with the ordinary carburetor.

Various changes may be made in the embodiment of the invention hereinabove described without departing from or sacrificing any of the advantages of the invention defined in the following claims.

I claim:

1. In a device of the class described, the combination of a generally cylindrical separating chamber, means for admitting a fuel mixture to said chamber and arranged to cause a whirling motion of the mixture in said chamber, an outlet tube extending from said chamber for withdrawing the gaseous fuel mixture therefrom, a jacket surrounding said separating chamber, means adapted to circulate a heating medium through said jacket, heat absorbing flanges projecting from the wall of said separating chamber into said heating jacket, and means in said separating chamber for temporarily retaining the heavier particles of the mixture on the wall of said chamber.

2. In a device of the class described, the combination of a fuel separating chamber having a cylindrical wall and end walls, a fuel inlet passage entering said chamber substantially tangentially to create a whirling motion of the fuel therein, an outlet for withdrawing the gaseous fuel mixture from said chamber, a heating jacket surrounding the circumference of said chamber and arranged to heat only said cylindrical wall, heating flanges projecting from said cylindrical wall into said heating jacket, and a plurality of grooves in said chamber substantially normal to the flow of mixture therethrough for retaining the liquid fuel deposited upon the walls of said chamber.

3. In a device of the class described, the combination of a first housing forming a cylindrical separating chamber, a heating jacket surrounding said separating chamber, said first housing having a fuel passage communicating with said separating chamber and having a heating fluid passage communicating with said jacket, and a second housing member secured to said first hous-

ing member, said second housing member having a second fuel passage communicating with said separating chamber and having a second heating fluid passage communicating with said jacket.

4. In a device of the class described, the combination of a first housing member defining a cylindrical separating chamber and a heating jacket surrounding said chamber, a tangential fuel inlet entering said chamber through said housing member, a passage for circulating a heating fluid through said jacket, a removable cover closing one end of said separating chamber, a second housing member secured to said first housing member at the other end of said separating chamber, said second housing member having an axial fuel outlet projecting into said separating chamber, and means for releasably securing said housing members together.

5. The combination of a separating chamber having a substantially cylindrical wall and a fuel inlet passage arranged substantially tangential to said wall, an outlet tube projecting into said chamber and spaced from the cylindrical wall thereof, said wall having a recess therein for retaining the liquid fuel deposited from said fuel mixture on said wall, and means whereby said wall may be heated.

6. The combination of a separating chamber having a substantially cylindrical wall and an inlet passage arranged substantially tangential to said wall, an outlet tube arranged substantially axially of said chamber and spaced from said wall, transverse channels in said wall, and means whereby said wall may be heated.

7. A fuel treating device comprising a chamber having a cylindrical wall, and end walls, means for heating only the cylindrical wall, means to admit a fuel mixture thereto and outlet means leading from said chamber at a point whereby the heavier particles only of the mixture are retained temporarily on said cylindrical wall.

8. A fuel treating device comprising a chamber having a peripheral heated wall and end walls, means for admitting a fuel mixture thereto and for causing the heavier particles only to contact with said heated wall, and circular grooves to trap said particles on said wall to form an insulating fog between the wall and the remainder of the fuel mixture passing thru the chamber.

In witness whereof, I hereunto subscribe my name this 20th day of October, 1919.

FRANK C. MOCK.
